UNITED STATES PATENT OFFICE.

VLADIMIR V. MESSE, OF WAUWATOSA, WISCONSIN.

APPARATUS FOR RAISING SUNKEN VESSELS.

1,288,107.

Specification of Letters Patent. Patented Dec. 17, 1918.

Application filed May 14, 1918. Serial No. 234,384.

To all whom it may concern:

Be it known that I, VLADIMIR V. MESSE, a citizen of the United States, residing in Wauwatosa, in the county of Milwaukee and 5 State of Wisconsin, have invented certain new and useful Improvements in Apparatus for Raising Sunken Vessels, of which the following is a specification.

The present invention relates to an apparatus for raising sunken vessels, and has for its object to provide a device of this character which embodies novel features of construction whereby a grapple member after being lowered to the proper depth can be 15 driven into an operative engagement with the hull of the sunken vessel by the ignition of an explosive charge, thereby avoiding the necessity of employing divers, and enabling vessels to be raised from depths which are 20 too great or under unfavorable existing conditions.

Further objects of the invention are to provide a device of this character which can be readily lowered into operative position, which can be used effectively for the raising of steel vessels or of vessels having heavy metal plates on the hull thereof, which enables a firm hold to be obtained upon the sunken vessel for the purpose of lifting the 30 same, and which is thoroughly dependable in its operation.

The herein illustrated and described preferable embodiment of the principles of the invention is but one of other possible structural arrangements that may be adopted for carrying the invention into practical effect. For a full understanding of the invention reference is to be had to the following description and accompanying drawing, in 40 which:—

Figure 1 is a side elevation of a grapple member constructed in accordance with the invention, portions being broken away and shown in section to illustrate more clearly 45 the details of construction.

Fig. 2 is a similar view looking at the grapple member from a position at right angles to that of Fig. 1.

Corresponding and like parts are referred 50 to in the following description and indicated in all the views of the drawings by the same reference characters.

Referring to the drawing, which illustrates one out of many possible embodiments 55 of the invention, the numeral 1 designates a barrel which is closed at its upper end and

provides an explosion chamber 2. A piston 3 is slidably mounted within the barrel 1, said piston being connected to the upper end of a plunger 4 which extends downwardly 60 through the lower end of the barrel and terminates in a flat head 5 which is preferably integral with the plunger. This head 5 has a knife edge 6 at the bottom thereof and is slidable through a combined 65 guide and hoisting collar 7.

The piston 3 is provided with suitable packing means such as a copper gasket 8 which is held in position by a ring 9, and the plunger 4 is rigidly connected to the 70 piston, being shown in the present instance as having a threaded connection 10 therewith. The lower end of the barrel 1 is initially closed by a plate 11 which is secured at its periphery to the barrel by suitable fastening means such as the screws 12, 75 a gasket 13 being interposed between the plate and the barrel to provide a watertight connection therewith. The plunger 4 extends centrally through the plate 11 and 80 is shown as having a threaded connection therewith. A cushioning washer 15 of wood or like material surrounds the plunger 4 and is arranged immediately above the plate 11, a metal washer 16 being superposed upon 85 the wooden washer, and the two washers 15 and 16 being positioned in a slightly flared portion at the mouth of the barrel so as to be held in proper position by an interior shoulder 17 in the barrel. 90

The exterior of the barrel 1 is provided with laterally projecting eyes or keepers 18 through which a pair of hoisting cables 19 are threaded, the lower ends of the cables being secured to wings 20 which project laterally from the collar 7. Set screws 21 may be threaded in the collar 7 and screwed into a light frictional engagement with the head 5 of the plunger to support the head and barrel in proper position while the grapple 100 member is being lowered as a unit into engagement with the hull of the sunken vessel to be raised. The frictional engagement between the set screws and the head is just sufficient to support the parts in proper position, and the set screws must not be tightened to a sufficient extent to interfere with the forcible driving of the head 5 through the collar 7 upon the ignition of a powder charge in the explosion chamber 2 of the 110 barrel 1.

A series of slots 22 are formed in the flat

head 5 above the cutting edge 6 at the bottom thereof, and a dog 23 is pivotally mounted within each of the slots, said dogs being all supported upon a transverse pivot 5 pin 24 and being arranged to have the upper ends thereof swung outwardly into the operative position by springs 25. When the dogs are swung upwardly into a vertical position, as indicated by full lines on Fig. 2, 10 they are completely housed in the head 5 so that the head can pass freely through the collar 7 or any opening which may be formed by the cutting edge 6 of a sufficient size to receive the body of the head. The 15 lower ends of the dogs 23 are formed with extensions 26 which constitute stop arms and coöperate with stop shoulders 27 at the lower ends of the slots to limit the outward swinging movement of the dogs. A portion of the 20 dogs 23 swing outwardly on one side of the head, while the remainder of the dogs swing outwardly on the opposite side of the head, the open position of the dogs being indicated by dotted lines on Fig. 2. The dogs will 25 swing upwardly to admit of the head passing through a small opening, although as soon as the head has passed through the opening the dogs will expand into operative position and prevent withdrawal of the head 30 through the opening.

The upper end of the barrel 1 is formed with an opening within which an ignition plug 28 is fitted, said plug being provided at its lower end with a cap 29 which projects 35 into the barrel and contains a charge of fulminate of mercury, or similar material. A pin 30 is slidable in the plug and arranged under a stem 31 which extends upwardly through the top of the plug, a stuffing box 32 being provided to insure a water-tight 40 joint. The upper end of the stem 31 is adapted to be engaged and pushed downwardly by a lever 33 which is pivoted between its ends upon a suitable bracket 34. 45 In the present instance this bracket is shown as being carried by a collar 35 which is rotatable on the plug 28 and adapted to be secured in proper position by a set screw 36. A firing rod 37 extends along the barrel 1 50 upon the exterior thereof, the upper end thereof being pivotally connected to the lever 33, while the lower end thereof passes through a guide eye 38 and is deflected inwardly at 37° to a point adjacent the collar 55 7, the extremity of the rod projecting slightly below the collar.

In the operation of the device the chamber 2 of the barrel is filled with a charge of powder or like material and the parts adjusted as indicated by Fig. 1 of the drawing. 60 The grapple member is then lowered as a unit into engagement with the sunken vessel which it is desired to raise. When the grapple member contacts with the sunken vessel 65 the firing rod 37 is moved upwardly and the

lever 33 caused to force the stem 31 and pin 30 of the ignition plug downwardly, thereby causing the fulminate of mercury to ignite the powder charge. The explosion of this powder charge forces the piston 2 and plunger 4 violently downward, separating the plate 11 from the lower end of the barrel or driving the plunger through its threaded connection with the plate. At the same time the head 5 is driven through the guide collar 7 and caused to penetrate the portion of the sunken vessel with which the grapple member has been brought into contact. As previously explained, the dogs 23 will permit the head to pass readily through the vessel, although they will expand and prevent the head from being withdrawn from the vessel. The recoil of the explosion will force the barrel 1 upwardly, and the wooden washer 15 will serve to partially absorb the shock incident to the tearing away of the connections at the lower end of the barrel, as previously explained. Where a heavy powder charge is necessary it may be desirable to provide some means such as the wings 39 to increase the resistance of the barrel to the water and assist the same in taking up the recoil. Under some conditions it may be found desirable to lower several of the grapple members at the same time and simultaneously ignite the explosive charges by electrical means, although this is only one of many possible modifications which are entirely within the scope of the invention.

Likewise structural changes may be resorted to without departing from the spirit and scope of the invention, as defined by the following claims.

Having thus described the invention, what I claim as new and desire to secure by Letters Patent, is:—

1. A device for raising sunken ships including a hoisting cable, a ship penetrating head operatively connected to the hoisting cable, and explosive actuated means including a loosely mounted barrel for driving the penetrating head into the ship.

2. A device for raising sunken ships, including a hoisting cable, a ship penetrating head operatively connected to the hoisting cable, and explosive actuated means including a barrel slidably mounted on the cable for driving the penetrating head into the ship.

3. A device for raising sunken ships, including a hoisting cable, a ship penetrating head having a sliding connection with the hoisting cable and provided with a piston, a barrel receiving the piston and loosely mounted upon the cable, and means for igniting an explosive charge into the barrel for driving the penetrating head into the ship.

4. A device for raising sunken ships, including a hoisting cable, a guide collar con-

nected to the hoisting cable, a ship penetrating head slidable through the guide collar, expansible dogs carried by the ship penetrating head and normally held in a retracted position by the guide collar, a piston on the ship penetrating head, a barrel receiving the piston and slidable upon the cable, and means for igniting the explosive charge in the barrel to drive the penetrating head into the ship.

5. A device for raising sunken ships, including a hoisting cable, a guide collar carried by the hoisting cable, a ship penetrating head slidable through the guide collar, expansible dogs carried by the penetrating head and normally held in a retracted position by engagement with the collar, and explosive actuated means for driving the penetrating head through the collar into the ship.

10. A device for raising sunken ships, including a hoisting cable, a ship penetrating head operatively connected to the hoisting cable, explosive actuated means for driving the penetrating head into the ship, and trip means actuated by engagement with the ship for igniting the explosive.

15. A device for raising sunken ships, including a barrel inclosing an explosion chamber, a piston mounted within the barrel, a head carried by the piston and adapted to be driven into the sunken ship by the ignition of a powder charge in the explosion chamber, an ignition plug applied to the barrel and including a firing pin, a lever for actuating the firing pin, and a slidably mounted firing rod operatively connected to the lever and extending downwardly below the head for engagement with the sunken ship when the device is in operative position.

20. A device for raising sunken ships, including a barrel having an open lower end and inclosing an explosion chamber, a piston mounted within the barrel, a plunger connected to the piston and extending through the open end of the barrel, a head carried by the plunger, a plate initially closing the lower end of the barrel, said plate being adapted to be torn away and the head 25 to be driven into the sunken ship by the

ignition of a powder charge in the explosion chamber, and hoisting means connected to the head.

9. A device for raising sunken ships, including a barrel inclosing an explosion 55 chamber, a piston mounted within the barrel, a head carried by the piston, a guide collar loosely surrounding the head, means for igniting a powder charge in the explosion chamber to drive the head through the guide 60 collar into the sunken ship, and hoisting means connected to the guide collar, said guide collar engaging the piston when drawn upwardly.

10. A device for raising sunken ships, including a barrel inclosing an explosion 65 chamber, a piston mounted within the explosion chamber, a head carried by the piston, a guide collar loosely surrounding the head, means for igniting a powder charge in 70 the explosion chamber to drive the head into the sunken ship, expansible dogs on the head to prevent withdrawal thereof from the ship, and hoisting cables connected to the collar, said collar being adapted to engage 75 the piston when drawn upwardly, and the barrel being slidable on the hoisting cables.

11. A device for raising sunken ships, including a hoisting cable, a ship penetrating head carried by the hoisting cable, explosive 80 actuated means including a barrel slidable upon the cable for driving the penetrating head into the ship, ignition means for the barrel, and trip means controlling the ignition means and including a rod projecting 85 downwardly at one side of the penetrating head for engagement with the sunken ship.

12. A device for raising sunken ships, including a hoisting cable, a guide collar connected thereto, a penetrating head slidable 90 through the guide collar, explosive actuated means including a barrel slidable upon the cable for driving the penetrating head into the ship, ignition means for the barrel, and trip means controlling the ignition means 95 and including a rod extending downwardly at one side of the barrel and guide collar for engagement with the sunken ship when the device is in operative position.

VLADIMIR V. MESSER.
